CLAIM

The ornamental design for a portion of a vehicle interior, as shown and described.

DESCRIPTION

FIG. 1 is a left side elevational view of a portion of a vehicle interior;

FIG. 2 is a right side elevational view of the portion of a vehicle interior;

FIG. 3 is a perspective view of the portion of the vehicle interior;

FIG. 4 is a top plan view of the portion of the vehicle interior;

FIG. 5 is a perspective view of the portion of a vehicle interior;

FIG. 6 is a perspective view of the portion of a vehicle interior; and,

FIG. 7 is a rear elevational view of the portion of the vehicle interior.

The vehicle shown in broken lines is for environmental subject matter only and forms no part of the claimed design. The shade and contour lines in the drawings show contour and not surface ornamentation of the claimed design. The ornamental design as shown and described includes the mirror image thereof.
